UNITED STATES PATENT OFFICE

JAMES L. KNIGHT, OF SCHENECTADY, NEW YORK, ASSIGNOR TO GENERAL ELECTRIC COMPANY, A CORPORATION OF NEW YORK

REFRIGERATOR CABINET

Application filed April 12, 1927. Serial No. 183,205.

My invention relates to refrigerator cabinets and an object of my invention is the provision of an improved refrigerator cabinet which is simple, durable and thermally efficient.

It has been the practice heretofore to construct refrigerator cabinets having inner and outer metal wall members with a heavy framework extending between the wall members. In order to obtain the necessary rigidity of the cabinets the framework was of large cross-section which provided such a large path for the transfer of heat into the cabinets that under favorable conditions about one-third of the heat leakage into the cabinet was due to conduction through the framework. The portion of the framework adjacent the outer wall of the cabinet was reduced in temperature below the dew point of the surrounding air which caused considerable condensation of moisture thereon. The material of the framework was not impervious to moisture so that the moisture condensed thereon was absorbed to a large extent. This caused the heat conductivity of the framework to be greatly increased and caused warping thereof so that the doors of the cabinet no longer fitted the openings resulting in leakage of air into the cabinet. Paint, varnish and other protective coatings were used on the framework to minimize the absorption of moisture, but this was not satisfactory as the condensation of moisture on the surfaces soon caused the coating to flake off, particularly under humid conditions. Moreover, the protective coatings were very objectionable as they frequently tainted food placed in the cabinet.

The object of my invention is to provide an improved cabinet construction which will minimize the leakage of heat into the cabinet and which will not be subject to the above-mentioned disadvantages incident to the use of such frames. I accomplish this by employing a refrigerator wall construction having inner and outer metal wall members which are placed apart and another wall member of a non-metallic non-hydroscopic material having low heat conductivity and

extending between the inner and outer wall members to form a closure between them.

My invention will be better understood from the following description taken in connection with the accompanying drawings, and its scope will be pointed out in the appended claims.

In the drawings, Fig. 1 shows by way of illustration an electric refrigerating machine having a cabinet embodying my invention; Fig. 2 is an enlarged detailed sectional view taken on line 2-2 of Fig. 1; Fig. 3 is a similar view taken on line 3-3 of Fig. 1; and Fig. 4 illustrates a modification.

The machine illustrated in Fig. 1 comprises the cabinet 1 and the refrigerating mechanism 2. The cabinet has an opening in the top covered by the door or cover 3 supporting the mechanism and has a side opening closed by the door 4. The cabinet including the doors I construct with inner and outer metallic casings or walls preferably of steel, the inner casing 6 being spaced from the outer casing 7 and the space filled with suitable heat insulating material 8, such for example as cork, which may be inserted in the form of built-up slabs or filled in loose. I have found that in refrigerator cabinets as commonly constructed a large proportion of the heat entering the cabinet is transmitted thereto by the members forming the door edges and the door jambs, apparently little attention having been given to this path of heat flow. With a cabinet having metallic inner and outer walls the heat transfer is more pronounced than in cabinets having all wood walls inasmuch as the heat is more readily conducted to and away from the aforesaid door edge and jamb forming members by which it enters the cabinet. In my cabinet I reduce the amount of heat thus entering the cabinet by keeping the metal of the inner and outer walls separated at the door edges and jambs or frames and connecting the walls at those points by a wall member comprising thin strips of a suitable non-metallic non-hydroscopic material having poor heat conductivity which forms a closure for the space between the metal walls whereby they provide restricted paths for heat entering the

cabinet at those points and resists deterioration by moisture. For this purpose I have found that resinous products are admirably well adapted, for in addition to having relatively low thermal conductivity they have a uniform composition, can be made in a variety of colors, whereby the necessity of painting may be avoided, do not absorb or give off odors and have such strength that they can be used in thin sheets arranged in the direction of heat flow thereby further reducing the amount of heat transferred. Among the resinous products I have found the glycerides and the phenolic resins, which it will be understood are used with any suitable filler material, or to bind together thin laminae of paper, fabric or the like forming a sheet of material, such for example as those known under the trade names Glyptal, Bakelite, Textolite, etc. to be particularly well suited for the present use in that being unaffected by moisture and heat changes, strips formed thereof do not swell or warp when in use.

The strips 9 are secured at opposite edges thereof to the respective metallic walls by any suitable means such for example by the screws 10 which I have shown threaded into narrow inward flanges 11 of the metal walls, the strips forming in effect a continuous surface around the edge of the doors 3 and 4 and also constituting the door jamb as shown in Fig. 3. In Fig. 2 I have omitted the strip forming the jamb since this closure is intended to remain permanently closed. I have shown the strips forming the door jamb in Fig. 3 as substantially equal in width to the spacing of the inner and outer walls. The doors I have shown having a thin overhanging edge portion 12, the strips 9 in that case having a width a little less than the spacing of the two walls but approximately equal thereto. Suitable gaskets 13 are provided against which the doors close. I may find it desirable principally for the sake of appearance to cover the corners of the door and door jambs, that is, where the strips 9 meet, with trimming such for example as thin strips of Monel metal which metal also has a low heat conductivity.

With the construction described above it is unnecessary to provide additional means for tying or securing together the inner and outer casings of the cabinet, the space between the casings being thus left free to be packed with the heat insulating material.

In the modification shown in Fig. 4 I have shown in cross section a double door arrangement, the one door fitting against the other when in closed position. By this construction no central or intermediate post is necessary and as a result the number of paths by which heat is transferred into the cabinet at this point is reduced one half. Doors 15 and 16 are hinged at 17 to the sides of the cabinet and are provided at opposite edges with

strips 9 such as shown in Fig. 3 and the door jambs are likewise formed of similar strips.

What I claim as new and desire to secure by Letters Patent of the United States, is,—

1. A refrigerator cabinet having a door and comprising spaced inner and outer metallic walls, heat insulating material between the walls, and thin strips of a resinous product connecting together said inner and outer walls peripherally of said door, said strips forming the sole connection between the respective walls. 70

2. A refrigerator cabinet having a door comprising inner and outer spaced metallic walls, heat insulating material therebetween, the edge portion of said door consisting of thin strips of a resinous product secured at their opposite edges to the respective inner and outer walls and having a width approximately equal to the spacing of the walls. 80

3. A refrigerator cabinet having a door and comprising spaced inner and outer metallic walls, said cabinet having a thin strip of a resinous product forming the connection between said inner and outer walls at said door. 90

4. A refrigerator cabinet having a door and comprising spaced inner and outer metallic casings, heat insulating material between said casings, an opening frame for said door formed of a thin strip of a resinous product secured at opposite edges to the respective inner and outer casings. 95

5. A refrigerator cabinet having spaced metallic inner and outer walls, a door comprising two cooperating door members hinged at their outer edges and adapted to engage each other at their adjacent edges, an opening frame for said doors and the edge portions of said door members being formed of thin strips of a resinous product. 100

6. A refrigerator cabinet having inner and outer metal walls spaced apart and provided with a door opening, a frame for the door opening consisting of a thin non-hydroscopic non-metallic material having low heat conductivity and being impervious to moisture, said frame extending through the door opening and connecting said inner and outer walls to form a closure between them. 110

7. A refrigerator cabinet having inner and outer metal walls spaced apart and provided with a door opening, a frame for the door opening consisting of a thin non-hydroscopic non-metallic material having low heat conductivity and being impervious to moisture, said frame having flat surfaces extending through the door opening and connecting said inner and outer metal walls to form a closure between them. 120

8. A refrigerator cabinet having inner and outer metal walls spaced apart and provided with a door opening, said inner and outer walls having flanges about the door opening 130

and a frame for the door opening extending therethrough and consisting of a thin non-hydroscopic flat strip of non-metallic material impervious to moisture secured to said flanges, said strip being of low heat conductivity and connecting the flanges of said inner and outer walls to form a closure between them.

9. A refrigerator cabinet having inner and outer metal walls spaced apart and provided with a door opening, said inner and outer walls having flanges about the door opening, and a frame for the door opening consisting of flat thin strips of a resinous product secured to said flanges, said strip extending through the door opening.

10. A refrigerator cabinet having inner and outer metal walls spaced apart and provided with a door opening, a door in said opening having inner and outer metal walls, frames for said door and door opening, each consisting of thin strips of non-hydroscopic non-metallic material having low heat conductivity, said frames extending through said door opening and being secured to said inner and outer walls of said cabinet and said door respectively.

11. A refrigerator cabinet having inner and outer metal walls spaced apart and provided with a door opening, a door in said opening having inner and outer metal walls, frames for said door and door opening, each consisting of flat thin strips of a resinous product secured to said metal walls and extending through the door opening.

12. A refrigerator wall construction having an inner metal wall member, an outer wall member spaced therefrom, and another wall member of a non-metallic non-hydroscopic material having low heat conductivity and extending between the inner and outer wall members to form a closure for the space between said wall members.

13. A refrigerator wall construction having an inner metal wall member, an outer metal wall member spaced therefrom, and another wall member of a resinous product extending between the inner and outer wall members to form a closure for the space between said wall members.

14. A refrigerator cabinet having a door opening and a door therefor, said cabinet and door each having inner and outer metal walls, and other walls of a non-metallic non-hydroscopic material of low heat conductivity, said other walls extending between the inner and outer metal walls of said cabinet and door respectively to form a closure for the space between said metal walls.

15. A refrigerator cabinet having a door opening and a door therefor, said cabinet and door each having inner and outer metal walls, and other walls of a resinous product extending between the inner and outer metal walls of said cabinet and door respectively

to form a closure for the space between said metal walls.

In witness whereof, I have hereunto set my hand this 11th day of April, 1927.
